UNITED STATES PATENT OFFICE

NELS T. NELSON, OF ATTLEBORO, MASSACHUSETTS, ASSIGNEE TO J. F. STURLY'S SONS COMPANY, A CORPORATION OF MASSACHUSETTS

EXTENSION DEVICE

Application filed December 5, 1930. Serial No. 500,293.

This invention relates to an extension device for a wrist watch strap; and has for its object to provide means by which an extension may be had by the unfolding of parts hereof as disclosed in my Patent No. 5 1,739,680, dated December 17, 1929, and yet be thinner and of less bulk.

A further object of the invention is the provision of a readily releasable clamp for the strap with other parts of the construction so arranged as to receive this clamp without its increasing the thickness of the device.

A still further object of the invention is the arrangement and shape of certain sections of the device to receive other sections, whereby different portions of the device are accommodated and the same is thinner in its final form.

With these and other objects in view, the invention consists of certain novel features of construction, as will be more fully described, and particularly pointed out in the appended claims.

In the accompanying drawings:

Fig. 1 is a top plan view of the extension device in folded position.

Fig. 2 is a plan view of the extension device in unfolded position looking at the top thereof.

Fig. 3 is a view similar to Fig. 2 looking at the under side of the device.

Fig. 4 is a central longitudinal section.

Fig. 5 is a central transverse section on line 5—5 of Fig. 1.

Fig. 6 is a perspective view partly broken away illustrating the folding arrangement of the different sections of the device.

In the use of wrist watch straps, extension devices are employed for temporarily lengthening the encircling size of the strap to permit the same to be passed over the hand of the wearer without completely detaching and separating any of its parts. In such a construction, it is desirable to provide a sufficient enlargement to permit the same to be easily removed from the hand, one of which is short in length and of minimum thickness for comfort upon the wrist; and in order to accomplish these desirabilities, I have provided

several sections, the majority being of sheet stock or plates formed to lie closely one upon the other, and I have arranged these sections so as not to fold the entire length of one another but to pile adjacent one end and I have then offset or formed a step in another of the sections to receive these folded sections on one side while a securing device for the strap is received on the other side of the plate, whereby to provide a structure of minimum thickness and one which can be formed thinner than the structure of my Patent No. 1,739,699, dated December 17, 1929; and the following is a detailed description of the present embodiment of this invention illustrating the preferred means by which these advantageous results may be accomplished:

With reference to the drawings, 10 designates one strap part and 11 another strap part with an extension device secured therebetween. This extension device comprises a body section 12 and a cover section 13 suitably held together in folded relation by detents 14 extending into recesses 15 to increase the frictional engagement between side walls 16 and 17 of the channel shaped sections which telescope together. A pair of plates 18 and 19 are hinged together as at 20, and hinged to the end of the body section 12 as at 21, to fold therewith, as illustrated in Fig. 4, the length of the section 18 being such as to cause the sections to extend but a portion of the length of the body section 12 placing the hinge joint 20 thereon intermediate the ends of the body.

An intermediate plate section 22 is hinged to the body section 12 and the cover section 13 to join the two together and permit them to fold inwardly, as illustrated in Fig. 4. The section 22 is so formed or bent intermediate its ends that one part of the plate section is offset from the other part as by a step 23 disposing one portion 24 of the plate 22 substantially parallel with the body and over the sections 18 and 19 with the other portion 25 more closely adjacent the body section 12, thus forming a more compact arrangement of the sections and providing a space over the portion 25 to receive the pivotally mounted clamp 26 for gripping the strap 10.

part 10 to hold the same in engagement with the cover section of the device. It will be clearly apparent from Fig. 4, the relative position of the clamp and portion 25 and the manner in which the clamp is accommodated by the offset as herein illustrated.

The plate 19 is secured to the strap part 11 at 27 by any suitable structure, such as a clamp 28 pivoted in the ears 29 thereof.

10 The hinges of the different sections in the structure herein disclosed are so arranged as not to contact or pile one upon the other while the offset section parts connecting the covering and body provides a means for receiving the strap clamp and the other folding extension plates to permit closer engagement of the parts and produce a device of the minimum thickness.

15 The foregoing description is directed solely towards the construction illustrated, but I desire it to be understood that I reserve the privilege of resorting to all the mechanical changes to which the device is susceptible, the invention being defined and limited only by the terms of the appended claims.

20 I claim:

25 1. In a wrist strap, an extension device comprising a body section, a plate hinged to one end thereof to fold thereover a portion of the length thereof, a cover section, and an intermediate plate hinged to the other end of said body section and to said cover section connecting the two together and so formed intermediate its ends that one part of the plate is offset with reference to the other as to lie along said body section and over the top of said plate when folded over the body section.

30 2. In a wrist strap, an extension device comprising a body section, a plurality of hingedly connected plates hinged to one end thereof to fold thereover a portion of the length thereof, a cover section, and an intermediate plate hinged to the other end of said body section and to said cover section connecting the two together and so formed intermediate its ends that one part of the plate is offset with reference to the other as to lie along said body section and over the top of said plates when folded over the body section.

35 3. In a wrist strap, an extension device comprising a body section, a plate hinged to one end thereof to fold thereover a portion of the length thereof, a cover section, a clamp on said cover section for attaching a wrist strap thereto, and an intermediate plate hinged to the other end of said body section and to said cover section connecting the two together and so formed intermediate its ends that one part of the plate is offset with reference to the other as to lie along said body section and receive said clamp on one side and the folded-in plate on the other side with the offset portion between said receiving por-

tions, and means for securing an end of the strap to said plate.

4. In a wrist strap, an extension device comprising a body portion, a plurality of hingedly connected plates hinged to one end thereof to fold thereover a portion of the length thereof, a cover section, a clamp on said cover section for attaching one end of a wrist strap thereto, and an intermediate plate hinged to the other end of said body section and to said cover section connecting the two together and so formed intermediate its ends that one part of the plate is offset with reference to the other as to lie along said body section and receive said clamp on one side and the folded-in plates on the other side with the offset portion between said receiving portions, and means for securing the other end of the strap to one of said plates.

85 In testimony whereof I affix my signature.
